UNITED STATES PATENT OFFICE.

MATTHEW GRISWOLD, JR., AND JOHN C. HOLLANDS, OF ERIE, PENNSYLVANIA, ASSIGNORS TO THE GRISWOLD MANUFACTURING COMPANY, OF SAME PLACE.

DESIGN FOR A WAFFLE-IRON SUPPORT.

SPECIFICATION forming part of Design No. 26,797, dated March 23, 1897.

Application filed December 10, 1896. Serial No. 615,218. Term of patent 7 years.

To all whom it may concern:

Be it known that we, MATTHEW GRISWOLD, Jr., and JOHN C. HOLLANDS, citizens of the United States, residing at the city of Erie, in 5 the county of Erie and State of Pennsylvania, have invented and produced a new and original Design for a Waffle-Iron Support; and we do hereby declare the following to be a full, clear, and exact description of the design, such 10 as will enable others skilled in the art to which it appertains to make and use the same, reference being had to the accompanying drawing, and to the letters of reference marked thereon, forming part of this specification.

15 The figure is a perspective view of a waffle-iron support embodying our design.

The leading feature of our design for a waffle-iron support consists of a circular shell flaring outward at the bottom and gradually 20 narrowing upward therefrom to the top thereof, so as to partake somewhat of the form of a frustum of a cone.

In the drawing illustrating our design, A is 25 a circular shell of metal, the bottom B of which flares outward and is considerably larger than the top C thereof. The bottom B is provided

on opposite sides thereof with handles D D. On opposite sides of the upper edge of the top C are vertical ears E and E', and between the ears E there is a slot e, and between the ears 30 E' there is a slot e', and on the outside of the shell A are vertical ribs F F at each side of the slot e', and at the bottom of the vertical ribs F F and secured to the outside of the bottom B of the shell A and inclosing the 35 lower ends of the vertical ribs F F is a cup-shaped projection G. In the upper edge C of the shell A, at opposite sides thereof and at right angles to the ears E and E', are half-circular slots c c.

Having thus fully described our design, what we claim, and desire to secure by Letters Patent of the United States, is--

The design for a waffle-iron support substantially as herein shown and described. 45

In testimony whereof we affix our signatures in presence of two witnesses.

MATTHEW GRISWOLD, JR.
JOHN C. HOLLANDS.
